UNITED STATES PATENT OFFICE.

LESTER J. YOUNG, OF OSWEGO, ILLINOIS, ASSIGNOR TO ALLSTEELEQUIP COMPANY, OF AURORA, ILLINOIS, A CORPORATION OF ILLINOIS.

SECTIONAL OUTLET-BOX FOR ELECTRIC CONDUITS OR WIRES.

1,205,589.

Specification of Letters Patent. Patented Nov. 21, 1916.

Application filed June 7, 1915. Serial No. 32,488.

To all whom it may concern:

Be it known that I, LESTER J. YOUNG, a citizen of the United States, and a resident of Oswego, county of Kendall, and State of Illinois, have invented certain new and useful Improvements in Sectional Outlet-Boxes for Electric Conduits or Wires, of which the following is a specification.

My invention relates to outlet boxes for electrical conduits or wires and more particularly to a box for this purpose that comprises one or more sections or units that are adapted to interlock with each other when assembled to form a complete outlet box.

The principal object of my invention is the provision of a sectional outlet box that is knockdown in construction, being made up of a plurality of interlocking units so that with a number of said units on hand a person may readily assemble an outlet box of any desired size.

Another object of my invention is the provision of a sectional outlet box that is so constructed that, by releasing the locking means, the same may be opened and the unlocked units thereof swung around so as to be removed or in order that access may be readily had to the interior.

Still another object of my invention is the provision of a novel bracket member whereby the box may be readily mounted in the wall or other suitable structure.

Other objects of my invention are the provision of a sectional outlet box that is easy to both assemble and knockdown, is comparatively inexpensive to manufacture, and is effective in its operation.

I prefer to accomplish these and other objects of my invention by the means and in the manner hereinafter fully described and as more particularly pointed out in the appended claims, reference being had to the accompanying drawings forming a part of this specification, wherein similar reference characters indicate the same elements throughout the various figures.

In the drawing: Figure 1 is a perspective view of my improved sectional outlet box, shown assembled with three units. Fig. 2 is a plan of one of the sectional units. Fig. 3 is a side elevation of the sectional unit shown in Fig. 2. Figs. 4 and 5 are detail views of my sectional outlet box, showing the same in closed and opened positions for the purpose of illustrating the manner of

disengaging the interlocking means, said figure being drawn to an exaggerated scale. Fig. 6 is a front elevation of the slide and pintle used in connection with the interlocking portion. Fig. 7 is a side view 60 thereof. Fig. 8 is a plan thereof.

Referring to the drawings, it will be seen that my outlet box is substantially rectangular in shape and hollow, and comprises a plurality of units consisting of correspondingly shaped intermediate units of substantially U-shape and substantially flat rectangular end units. The intermediate unit consists of a substantially U-shaped plate, the connecting member 10 of which 65 provides a suitable rear wall and the parallel arms or vertical members 11, arising from each of the end edges of member 10, provide the top and bottom walls of the outlet box. Suitable scores 12, are made in 70 the walls of the box of a substantially circular form, the arc described by said circle being incomplete so as to form a short neck 13 whereby the said portion inclosed within the score is retained in position until removed by tapping it out with a hammer or by other means. This will provide the 75 desired openings in the outlet box for the insertion of the conduits or wires.

The vertical edges of the members 11 are 80 provided with suitable outwardly bent knuckles 14 upon one edge, which, as shown in Fig. 2 of the drawings, are formed by bending the metal laterally to form a loop and pressing the inner edge 15 tightly 85 against the adjacent edge of the member 11. Horizontally opposite this knuckle and cut into the edge of member 11, is a shallow 90 elongated recess 16 of a width substantially corresponding with the thickness of the metal forming the member 11 so that, when the adjacent section or unit is fitted against the same, the portion 15 of the knuckle will seat flush in said recess 16 as clearly shown in Fig. 4. Below the recess 16 a knuckle 17 95 is formed substantially in the same manner as the knuckle 14 heretofore described and horizontally opposite said knuckle 17 and below the knuckle 14 is an elongated recess 18 100 corresponding in shape with the recess 16 and adapted to interfit or interlock with a knuckle 17 on the adjacent sectional unit.

When several intermediate units are assembled side by side, to form a box of large dimensions as illustrated in Fig. 1, the 110

knuckle 14 of the one unit will register with and be in axial alinement with the knuckle 17 of the adjacent unit so that a suitable pinte 19 may be inserted therein to lock the 5 sections or units together. This pinte 19 preferably comprises a suitable length of wire or the like, which after passing through the knuckles 14 and 17, is bent laterally outwardly to form lateral loop brackets 20 10 and is then bent upwardly and then downwardly to form an elongated vertical loop 21, the space 22 between the parallel members of the loop forming a guideway or slot in which a suitable set screw 23 is inserted 15 and which is prevented from leaving the said slot by means of the inturned end 24 of the wire forming said loop and pinte. The tightening of this set screw 23 will securely lock the pinte in position.

20 The end edges of the parallel members 11 of the intermediate units are provided with laterally disposed screw lugs 25 whereby a switch or the like may be secured to the box. The end units preferably comprise 25 plates 26 for closing the ends of the box after assembly, and said end units are provided on their end edges with knuckles 27 and 28 corresponding with the knuckles 14 and 17 heretofore mentioned and are likewise 30 provided with recesses 29 and 30, respectively below and above knuckles 14 and 17, in which portions of the adjacent knuckles are adapted to interfit.

When a box of ordinary dimensions is 35 desired, one intermediate U-shaped unit and two end units are provided and interlocked with each other in the manner set forth. In the event a larger box is desired more of the intermediate units may be assembled together with the two end units, closing the 40 ends thereof. In installing the box the loop brackets 20 are employed as screw-lugs whereby the box is attached to the framework of the building and when secured in 45 position the pintles are thus prevented from being withdrawn.

After assembly, when it is desired to open the outlet box to add another unit or for other purposes, all that it is necessary to 50 do is to loosen one of the screws 23 and move the respective slide until the end of the pinte forming a part thereof, disengages the knuckle 14 whereupon one or more units of the outlet box may be swung laterally 55 upon the pinte at the opposite meeting edges of the units until the edge 15 has disengaged its respective recess whereupon the units that have been swung around may be lifted off the pinte and the box is opened 60 so that the units may be readily assembled or disassembled. It will be observed that if

through accident or error a pinte should fall or gravitate out of one of its knuckles, the box will not become disassembled until the edge 15 on the opposite side has been 65 disengaged from its respective recess.

While I have illustrated and described herein certain specific means for carrying out my invention, it, of course, will be obvious, to others skilled in the art to which it 70 pertains, that numerous modifications or refinements thereof are possible without materially departing from the spirit of my invention. I therefore desire it understood that all such changes are contemplated within 75 in the scope of my invention as expressed in the appended claims.

What I claim is:—

1. A sectional outlet-box comprising a plurality of units, interlocking means provided upon their adjoining edges, a plurality of pintles, one being carried by each respective unit, each of which pintles engages the interlocking means of the unit adjacent that upon which it is carried, and means for locking 85 each pinte to its respective unit.

2. A sectional outlet-box comprising a plurality of substantially U-shaped units the edges of the parallel members whereof are provided with knuckles that are adapted to 90 register with corresponding knuckles upon the abutting units, a pinte engaging said registering knuckles and comprising a length of wire a portion whereof is bent back upon itself to provide a guideway, and a locking 95 member the shank whereof enters said guideway.

3. A sectional outlet-box comprising a plurality of units, knuckles on the abutting edges of each of said units adapted to register with each other, and locking means for 100 said knuckles comprising a length of wire, a portion whereof provides a pinte for said knuckles and the remaining portion whereof is bent laterally to provide a mounting 105 bracket for said box.

4. An outlet-box comprising one or more U-shaped units, substantially flat end plates therefor, the abutting edges of said units and end plates being recessed, knuckles adjacent 110 to and adapted to fit said recesses, and a pinte engaging said knuckles, a portion of said pinte bent laterally to provide a bracket whereby said box is mounted in position.

Signed at Oswego, county of Kendall and State of Illinois, this 28th day of May 1915.

LESTER J. YOUNG.
